ATTORNEYS.

UNITED STATES PATENT OFFICE.

GEORGE L. GARRIGUES, OF NEW YORK, N. Y.

DESIGN FOR A MIRROR-FRAME.

SPECIFICATION forming part of Design No. 13,564, dated January 30, 1883.

Application filed November 9, 1882. Term of patent 3½ years.

To all whom it may concern:

Be it known that I, GEORGE L. GARRIGUES, of the city, county, and State of New York, have invented and produced a new and original

5 Design for Mirror-Frames, of which the following is a specification, reference being had to the accompanying drawing, forming part thereof.

In the drawing my newly-invented design 10 is shown by a front view of the frame.

The frame is made with a center panel, A, for the mirror and side spaces, of smaller size, for receiving ornamental panels B. The frame may be covered with plush, and the 15 panel-spaces formed with bevel-edges. The essential features of the design are the outer

ornamental panels, B, which are placed at the sides of the center panel, said outer panels forming flower pieces, as shown, which may be painted on satin.

20

This design furnishes a highly-ornamental mirror-frame.

I claim—

The described design for mirror-frames, which consists in a central mirror-panel, A, 25 and the side panels, B, forming flower pieces, as shown.

GEO. L. GARRIGUES.
